METHOD OF FORMING VARIOUS UNITS
FROM STANDARDIZED BLANKS

Arthur L. Parker, Cleveland, Ohio

Application April 25, 1938, Serial No. 204,198

3 Claims. (Cl. 29—157)

The invention relates generally to the art of metal working and primarily seeks to provide a novel forged, cast or otherwise formed cast metal blank standardized so that a variety of units can be formed thererfrom, and a novel method of utilizing the blank in the formation of such units.

In the formation of tube or pipe couplings, valves and the like, it is the common practice to individually design and form the forging or casting to be worked up into each particular unit. This practice necessitates the use of individual hammer and anvil structures, in the case of forging, die structures in the case of die casting, and molds in other types of casting, for each unit to be made, and obviously the expense and labor necessarily expended in providing and handling this equipment is undesirably great.

An object of the invention is to provide a novel method of forming units comprising the formation of a standard blank embracing all design features of a variety of units to be made up, and the working of the standard blank to form the particular design of unit desired.

In the drawing—

Fig. 1 is a face view of a T-shaped standard blank constructed in accordance with the invention;

Fig. 2 is a view similar to Fig. 1 showing the blank of Fig. 1 worked to provide a unit of individual design;

Fig. 3 is a view similar to Fig. 2 illustrating the working of the blank to form a unit of another design.

In the practical development of the invention I provide a standardized unit generally designated 5, which in this particular illustration, is T-shaped and may be formed by any of the well known methods of drop forging, die casting, or in any other suitable manner.

The standard blank unit is formed to embrace the design features of a variety of individual tube coupling units. For this purpose the three legs 6, 7 and 8 of the T-shaped blank each is formed to include a non-circular head portion 9 and a protuberance 10 extending axially of the particular leg and beyond the head portion 9, as shown in Fig. 1.

In Fig. 2 of the drawing the standard blank unit has been worked to provide a particular design of pipe coupling. In this figure, the full lines indicate the finally worked individual coupling unit, and the dot and dash lines and shaded areas indicate the surplus metal portions of the standard blank removed initially in the forma-

tion of said unit. The formed unit includes an externally threaded male extension 11 at one end of the T, an internally threaded counterbore 12 at the opposite end of the T and communicating with a male seat 13 for effecting a flared end tube coupling, and another internally threaded counterbore 14 in the remaining leg of the T. In the formation of this unit the head of the T is initially bored as at 15, prior to the formation of the threaded counterbore 12, and the other leg of the T is bored as at 16 prior to the formation of the threaded counterbore 14.

In Fig. 3 of the drawing, I have illustrated the formation of another individual design of unit and in this illustration also the completed unit 15 is illustrated in full lines and the excess metal portions of the standard blank removed in the formation of the unit in dot and dash lines. In the formation of this unit the T-head is initially bored as at 17, the other leg of the T is bored as at 18, the metal of the vertical leg is reduced and the remaining portion of the leg worked to provide an externally threaded male extension 19, and each end of the T-head is worked to provide an externally threaded male extension 20 of individual design, including a coniform male seating portion 21.

From the foregoing description it is thought that the details of construction and advantages of my improved blank will be readily understood by those skilled in the art to which it relates, as well as my improved method which includes the formation of a standardized blank embracing all design features of a variety of units to be made up, and the working of the standard blank to form the particular design of unit desired.

What I claim is:

1. A method of forming tube coupling units comprising the formation of a standard blank with a plurality of legs, each leg including a non-circular head and a protuberance extending axially of the leg beyond the head, removing certain of the heads and protuberances, or portions thereof, to form a blank of particular design, and working the remaining portions of the legs to form from said standard blank a tube coupling of selected design.

2. A method of forming tube coupling units comprising the formation of a standard blank with a plurality of legs, each leg including a non-circular head and a protuberance extending axially of the leg beyond the head, removing the protuberances from any leg or legs, and inter-

nally working the head on such leg or legs, removing the non-circular head from the remaining leg or legs, and externally working such remaining leg or legs to form from said standard blank a tube coupling unit of selected design.

5 3. A method of forming tube coupling units comprising the formation of a standard blank with a plurality of individual bosses, each boss including a non-circular head and a protuberance 10 extended axially of the boss beyond the head,

removing the protuberances from any selected boss or bosses, and internally working the head on such boss or bosses to receive a tube or pipe, removing the non-circular head from the remaining boss or bosses and externally working such remaining boss or bosses to provide a male piece for a tube or pipe connection to form from said standard blank a tube coupling unit of selected design.

ARTHUR L. PARKER. 10
